UNITED STATES PATENT OFFICE.

ALEXANDER MAKEPEACE, OF FALL RIVER, MASSACHUSETTS.

MECHANISM FOR REMOVING WASTE YARN FROM BOBBINS.

SPECIFICATION forming part of Letters Patent No. 761,976, dated June 7, 1904.

Application filed December 18, 1903. Serial No. 185,669. (No model.)

To all whom it may concern:

Be it known that I, ALEXANDER MAKEPEACE, a citizen of the United States, residing at Fall River, in the county of Bristol and State of Massachusetts, have invented certain new and useful Mechanism to Remove Waste Yarn or Roving from Bobbins, of which the following is a specification.

My invention relates to mechanism for removing waste yarn or roving from bobbins, and has for its object the substitution of mechanical means for the manual operation known as "stripping" bobbins. The advantages of this substitution will be made apparent hereinafter.

Upon the removal of a bobbin from its shuttle more or less waste yarn remains upon the spindle portion near the head thereof. To strip this waste from the spindle, a boy with his hand grips the waste and spindle and drives the nose of the bobbin one or more times against some unyielding body, the hand, with its waste, moving toward the nose of the bobbin. When sufficiently loosened, the waste in one hand and the bobbin in the other are separated and then thrown into suitable receptacles therefor; but serious objections arise from this method of stripping. Thousands and thousands of bobbins soon have their lines destroyed by this pounding. Their noses being wooden, the exposed ends of the fibers become slivered and rough, and the yarn when running off over such rough and slivered noses, especially in spinning-frames, catches thereon and breaks. When in this condition, the noses must be repaired by having their ends turned down smooth; but this operation reduces the length of each bobbin. Further, this method of stripping works injury to the operative's hands. The pounding causes the waste to irritate and inflame the palm of the hand, which often becomes painfully sore. In some cases the above method cannot be used to strip off the waste yarn. This is especially true where the spindle of the bobbin is cylindrical instead of tapering. In such an event the operative resorts to a knife. He draws the point of the blade across the yarn-windings and repeats the operation in no careful manner until all are severed; but to accom-

plish this result he scores the wooden spindle, which only too soon becomes so weakened as to be rendered useless. In fine, the manual stripping destroys the lives of multitudes of bobbins, greatly reduces the efficiency of the bobbin by increasing the breakage of yarn, and seriously affects the physical condition of the hands of the operative. Now the purpose of my invention is to overcome these objections by substituting for this manual operation of stripping mechanical means to remove the yarn without injuring the bobbin, and by so doing I accomplish a great saving in the item of labor, in the lives of the bobbins, and in the breakage of yarn.

My invention resides in mechanism that will receive a bobbin having waste yarn thereon, seize the yarn, push the bobbin away therefrom, and leave the yarn behind, said mechanism being made up of jaws to move into and out of engagement with the waste yarn on the bobbin and a reciprocating apparatus to push the bobbin through and away from the closed jaws, the waste yarn remaining at the jaws.

Figure 1 is a perspective view of my invention, the parts being in position to begin removing waste from the bobbin. Fig. 2 shows a side elevation, the bobbin being shown in dotted lines. Fig. 3 represents a front elevation. Fig. 4 is a top plan, the jaws being shown in position to grip the waste on a bobbin. Figs. 5 and 6 are sectional details of the jaws, Fig. 5 showing the relations of jaws and waste at the beginning and Fig. 6 at the end of the operation of removing waste from the bobbin; and Fig. 7 shows how the jaws may be modified in form to be adapted to a different type of bobbin.

In the drawings illustrating the principle of my invention and the best mode now known to me of embodying said principle a table X supports the various gripping, reciprocating, and driving devices. Jaws a^1 are mounted in ways a^2 , fixed to the table X, and have in each of their two adjacent ends a curved beveled face, which with the top surface of the jaw forms a thin curved edge a^3 , as in Figs. 4, 5, and 6. Symmetrically pivoted to the jaw a^1 at a^4 are two levers a^5 a^6 , each of which

is also pivoted to the ways at a^6 . The jaw a in its outer end portion has secured therein a threaded yoke a^7 , which may be adjusted lengthwise of the jaw to change its relations thereto. A driving-lever a^8 in a plane at right angles to the jaws a a' is pivoted to the table, as at a^9 , and near its upper end portion is pivotally secured within the yoke a^7 , adjustably secured to the jaw a . Links a^{10} a^{10} connect this portion of said driving-lever to the free arms of the levers a^5 a^5 . The lower end portion of said driving-lever a^8 is in sliding engagement with a rocker-arm a^{11} , provided with an antifriction-roller a^{12} and secured to a rock-shaft a^{13} , loosely mounted on bearings on legs x x of the table X. A spring rock-arm a^{14} , fixed to said rock-shaft, is in sliding engagement with a sector-shaped cam a^{15} , mounted on a cam-shaft b and to be more particularly described later. When said jaws a a' are closed together, the axis of the opening formed by their curved adjacent edges a^3 a^3 is at right angles to the plane of the jaws. Below said jaws and coincident with said axis is that of a hollow cylindrical guide c , whose upper end portion is secured to the under side of the table-top and rigidly held in position by braces c' c' , fastened to the table-legs x x . The diameter of this guide c is large enough to receive the spindle z , with its waste z' , and to permit it to reciprocate freely. A push-rod c^2 is retained within this guide and has its lower end provided with an antifriction-roller c^3 . A circular cam c^4 , fast on said cam-shaft b , which shaft is in the plane of the axis of said guide c , engages said antifriction-roller c^3 and pushes said push-rod c^2 upward, the weight of the rod causing it to follow the cam c^4 in its descent. The length of the guide c and the rod c^2 is such that when the push-rod is in its lowest position the head of the bobbin is just above the curved gripping edges of the jaws. (See Figs. 2 and 5.) If desirable, the top of the push-rod may have some soft material c^5 , such as felt, fixed thereto to protect the nose of the bobbin when in contact with said push-rod. Secured to the cam-shaft is a gear b' , that meshes with a driving-gear d on driving-shaft d' , on which are fast and loose pulleys d^2 d^3 . The circular cam c^4 gives the push-rod c^2 the desired upward movement, while the sector-like cam a^{15} closes the jaws a a' by engaging the spring rock-arm a^{14} , which is operatively connected with said jaws a a' through the cam-shaft b , rocker-arm a^{11} , driving-lever a^8 , yoke a^7 , links a^{10} a^{10} , and levers a^5 a^5 . Said sector-like cam a^{15} is designed to operate through an angle of about sixty degrees during the period the circular cam c^4 , and hence the push-rod c^2 , are in their lowest positions. (See Figs. 1, 2, 3, and 4.) The jaws a a' are thus kept closed for, say, one-third of the upward stroke of the push-rod c^2 . When the sector-like cam a^{15} ceases to operate said arms and

said levers, a retractile spring a^{16} , connected with said driving-lever a^8 , pulls it in an opposite direction, and thus opens the jaws a a' and holds them open until the circular cam c^4 and its push-rod c^2 have reached their said lowest positions—i. e., the jaws are closed for about one-third of the upward stroke of the push-rod c^2 and are open for the balance of said upward stroke and the entire downward stroke of said push-rod c^2 . 75

A plate f , having a hole therethrough concentric with the cylindrical guide c and the curved edges a^3 of the jaws a a' , protects the operative's hands from being accidentally crushed between the reciprocating jaws. 80

The operation of my apparatus is as follows: Power being received through the fast pulley d^2 , it is transmitted through the gear-wheels d b' to the cam-shaft b and thence through the circular cam c^4 , which forces upward the push-rod c^2 and then permits the latter by reason of its weight to follow the cam back to its original and lowest position, where and when the sector-like cam a^{15} begins to move the spring rock-arm a^{14} , rock-shaft a^{13} , and rock-arm a^{11} , which in turn forces outwardly the lower portion of the driving-lever a^8 and the upper arm inwardly. This latter movement imparts, through the yoke a^7 , a similar movement to the jaw a and through the links a^{10} and levers a^5 an opposite movement to the other jaw a' . In short, the jaws a a' become closed. After the sector-like cam a^{15} has moved through an arc of about sixty degrees—that is, after the push-rod c^2 has moved up toward the curved edges a^3 of the jaws for about one-third of its stroke—said sector-like cam ceases to hold the jaws closed, and the retractile spring a^{16} , acting in a direction opposite to that of the cam c^4 , causes the jaws a a' to open until the push-rod c^2 returns to its lowest position. 100

To remove the waste z' from a bobbin z , the spindle of the latter is dropped into the guide c upon the cushioned top c^5 of the descending push-rod c^2 . When the latter reaches its lowest position, (see Figs. 1, 2, and 3,) the jaws a a' engage the top portion of the waste z' (see Figs. 1, 4, and 5) and the push-rod c^2 pushes the bobbin z up through the opening formed by the curved edges a^3 of the jaws a a' , all the waste z' remaining at said edges and the bobbin being completely divested of its waste yarn. (See Fig. 6.) The operative the moment the jaws open seizes the clean bobbin with one hand and the waste with the other and has ample time to remove them from the apparatus while the jaws are open. The same operation is rapidly repeated with succeeding bobbins. 115

To avoid breaking the machine and also to give some play to the jaws in case the diameter of the bobbin should vary from that of the kind being stripped, the rock-arm a^{14} is a spring. Should the thickest part of the bob- 120

bin accidentally be caught between the jaws, and the rock-arm were rigid, something would break. If the arm is a spring, this breakage is avoided. The same benefit would result if any 5 one member of the system of levers and connections operating the jaws were resilient. Further, by simply changing the length and diameter of the push-rod, the stroke of the cam, the shape and size of the gripping edges 10 of the jaws, as in Fig. 7, the operators can operate upon all kinds of bobbins—such, for example, as slubber, intermediate, fine-roving, jack, warp, and filling bobbins.

In fine, by employing the principle of my 15 invention, which is illustrated by the above-described machine, I can remove waste yarn from all kinds of bobbins without injuring them.

It will be evident that the principle of my 20 invention may be embodied in many forms without departing from the substance thereof.

Desiring to protect my invention in the broadest manner legally possible, what I claim is—

25 1. A mechanism, comprising jaws, whereby waste yarn on a bobbin may be seized and released by said jaws; mechanism whereby said jaws are caused to seize and release said waste; mechanism whereby said bobbin is pushed 30 through and away from said jaws; and driving mechanism coöperating with said jaw-operating and said pushing mechanisms, to open said jaws while the pushing mechanism is receding from said jaws, and to close said jaws 35 when said pushing mechanism approaches said jaws.

2. A mechanism comprising jaws, each of 40 which has an edge adapted to engage waste yarn on a bobbin; ways in which said jaws are movably mounted; mechanism to move 45 said jaws, and their adjacent gripping edges, toward and away from each other; mechanism whereby said bobbin is pushed between and away from said edges; and driving mechanism, coöperating with said jaw-operating and said pushing mechanisms, to open said jaws while the pushing mechanism is receding from said jaws, and to close said jaws when 50 said pushing mechanism is approaching said jaws.

3. A mechanism comprising jaws, whereby waste yarn on a bobbin may be seized and released by said jaws; a system of levers and links, operatively connected with said jaws; a 55 sector-like cam operating said system of levers and jaws; mechanism whereby said bobbin is pushed between and away from said jaws; driving mechanism, coöperating with said sector-like cam and its connecting system 60 of levers, and with said pushing mechanism, to open said jaws while said pushing mechanism is receding from said jaws, and to close

said jaws when said pushing mechanism is approaching said jaws.

4. A mechanism, comprising jaws, whereby 65 waste yarn on a bobbin may be seized and released by said jaws; a system of levers and links, operatively connected with said jaws; a cam-shaft; a sector-like cam, mounted on said shaft; a second cam mounted on said cam-shaft; a push-rod, operated by said second cam, to push the bobbin between and away from said jaws; a guide for said push-rod; said sector-like cam, and said second cam operating the push-rod, being so adjusted and 70 secured to said cam-shaft, that the sector-like cam begins to operate when the push-rod and its cam begin to approach the jaws, and ceases to operate before they recede from said jaws; and driving mechanism to operate said cam-shaft. 75

5. A mechanism, comprising jaws, whereby waste yarn on a bobbin may be seized and released by said jaws; a system of levers and links operatively connected with said jaws; a 85 sector-like cam operating to retract said system of levers and jaws; a retractile spring operating said levers and jaws in an opposite direction; mechanism whereby said bobbin is pushed between and away from said jaws; 90 driving mechanism, combined with said cam-operating and said pushing mechanisms to permit said spring to operate said system of levers to open said jaws while said pushing mechanism is receding from said jaws, and to 95 close said jaws when said pushing mechanism is approaching said jaws.

6. A mechanism comprising jaws, whereby waste yarn on a bobbin may be seized and released by said jaws; mechanism, whereby said 100 jaws seize and release said waste; and mechanism, whereby said bobbin is pushed between, and away from, said jaws.

7. A mechanism, comprising jaws, whereby waste yarn on a bobbin may be seized and released by said jaws; mechanism whereby said 105 jaws are caused to seize and release said waste; mechanism whereby said bobbin is pushed through and away from said jaws; and driving mechanism, coöperating with said jaw-operating and said pushing mechanisms to open said jaws while the pushing mechanism is receding from said jaws, and to close said jaws when 110 said pushing mechanism approaches said jaws; said jaw-operating mechanism, containing a resilient member therein, to prevent 115 breakage of said mechanism.

In testimony whereof I affix my signature in presence of two witnesses.

ALEXANDER MAKEPEACE.
